DESIGN FOR A PERFUME BOTTLE STOPPER
OR SIMILAR ARTICLE

John Herbst, New York, N. Y.

Application June 8, 1946, Serial No. 130,526

Term of patent 3½ years

(CL. D58—10)

To all whom it may concern:

Be it known that I, John Herbst, a citizen of the United States, residing in New York city, in the county of New York and State of New York, have invented a new, original, and ornamental Design for a Perfume Bottle Stopper or Similar Article, of which the following is a specification, reference being had to the accompanying drawing, forming part thereof.

Fig. 1 is a front view of a perfume bottle stopper or similar article showing my new design, and

Fig. 2 is the side view thereof.

The rear view of my perfume bottle stopper or similar article is substantially the same as the front view.

I claim:

The ornamental design for a perfume bottle stopper or similar article, substantially as shown and described.

JOHN HERBST.
